(57) **CLAIM**

The ornamental design for a modular back support system for bulletproof vests, backpacks and the like, as shown and described.

DESCRIPTION

FIG. 1 is a front view of a modular back support system for bulletproof vests, backpacks and the like, showing my design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is an exploded front perspective view thereof; and, FIG. 8 is a front perspective view of an alternate position thereof.

Any broken line illustration of environmental structure in the drawings is not part of the claimed design.
